UNITED STATES PATENT OFFICE.

LOUIS C. WITKOWSKI, OF WASHINGTON, DISTRICT OF COLUMBIA, ASSIGNOR
TO THE CROWN SELF-OPENING CAN COMPANY, OF WEST VIRGINIA.

BOX OR CAN.

SPECIFICATION forming part of Letters Patent No. 625,625, dated May 23, 1899.

Application filed December 6, 1898. Serial No. 698,454. (No model.)

To all whom it may concern:

Be it known that I, LOUIS C. WITKOWSKI, a citizen of the United States, residing at Washington, in the District of Columbia, have invented certain new and useful Improvements in Boxes or Cans; and I do hereby declare the following to be a full, clear, and exact description of the invention, such as will enable others skilled in the art to which it appertains to make and use the same.

My invention relates to improvements in boxes or cans which are provided with thin permanent covers, generally termed "tagger-tops," and which are designed for keeping the goods packed in the same hermetically sealed during transportation; and the invention consists of a novel arrangement of a knife or cutter which is provided on the tagger-top and which is designed to cut out the tagger-top when desired without the use of an auxiliary cutter.

In the accompanying drawings, Figure 1 is a perspective view of a can constructed in accordance with my invention and provided with a permanent tagger-top and a removable cover. Fig. 2 is a vertical section through the same. Fig. 3 is a top plan view of a cutter designed for use on a circular can. Fig. 4 is an enlarged detail view showing a means of securing the cutter to the tagger-top without piercing the same. Fig. 5 is a top plan view of a square box or can with my improved cutter applied to the same. Fig. 6 is an enlarged top plan view of the style of cutter which is employed on a square box or can. Fig. 7 is a vertical section through the handle portion of the arm carrying the cutter and showing the means of attaching the cutter to the handle so that the handle and cutter will be capable of revolving independently of the arm. Fig. 8 is a plan view of a portion of the outer end of the cutter-arm when constructed for use in cutting out a square can. Fig. 9 is a detail plan view of the handle portion, similar to the construction shown in Fig. 6; and Fig. 10 is a side elevation of the knife or cutter in detail, similar to the construction shown in Figs. 6 and 7. Fig. 11 is a perspective view of another modified form of my invention particularly designed for use on cans

not having a removable outer cover. Fig. 12 is a perspective view of a can of the same construction as shown in Fig. 11, but in the act of being opened. Fig. 13 is a vertical longitudinal section through a portion of the can, showing the same construction as represented in Fig. 11. Fig. 14 is an inverted plan view of the cutter. Fig. 15 is a sectional view showing a modified form of pivoting the cutter to the tagger-top, and Fig. 16 is a slightly-modified form of the construction shown in Fig. 11.

A in the drawings represents a box or can which is provided on its outer surface near its upper edge with an outwardly-extending projection *a* and with a permanent thin top or cover *B*, sometimes termed a "tagger-top." The box or can is also provided with a removable cover *C*, which closely fits said can and rests with its lower edge upon the peripheral projection *a*. An arm *D* is pivoted in the center of the tagger-top, as at *d*, and extends to nearly the periphery of the can. The arm is pivoted to the can in any suitable manner, either by a pin passed through the tagger-top and through an eye *d'* in the arm *D*, said pin being bent over to hold the said arm in place, or the arm may be pivotally secured to the tagger-top by forming a slight depression in the upper surface of the tagger-top, as at *d''* in Fig. 4, and soldering the pin in position in said socket, said pin being formed with a head *d'''* for that purpose. By this construction the tagger-top will not be punctured or pierced in any manner, which may be a preferable construction to the one first described, as it is very important that the goods in the box or can should be kept hermetically sealed, though I do not believe that the first construction would admit of any air getting into the can, for the reason that the solder used in securing the pin *d* in position would entirely seal the aperture made in the tagger-top.

The arm *D*, which is the one designed particularly for a round can, is made preferably in the manner shown in Fig. 3, in which construction it is stamped out of a single piece of suitable material, with its outer end turned downwardly to form a cutter *E* and having

laterally-extending portions d^4 , which latter are adapted to be turned up on the lines d^5 d^6 (shown in Fig. 3) for the purpose of forming a handle, as d^{12} . (Shown in Figs. 1 and 2.)

5 When the box or can is not provided with a removable cover C, the laterally-extending portions d^4 d^4 during transportation can be left in a flattened condition, so as not to interfere with packing, and when it is desired 10 to form these portions into a handle they can be readily turned up by the fingers of the operator, as the material would be sufficiently thin to readily admit of this; but when the box or can is provided with a removable 15 cover, as C, the portions d^4 d^4 can be turned up during the process of manufacture and left in said raised condition, as there will be sufficient space between the top of the tagger-tin and the under side of the removable 20 cover to admit of this. While I prefer to construct the arm D and cutter E all in one piece, yet it is obvious that the cutter might be constructed separately from the arm and suitably secured thereto, in which construction 25 the cutter might be made of a different material from the arm.

In Fig. 5 of the drawings I have shown my invention applied to a square box or can. In using the same on square cans it is of course 30 necessary that the arm should be capable of adjustment longitudinally and also that the knife should be capable of having a rotary movement. In order to accomplish this, I construct the arm D' with a longitudinal slot d^6 , through which the pivot-pin d^8 is passed. The arm D' is also provided near its outer 35 end with a circular aperture d^9 , as clearly shown in Fig. 8. The handle portion d^{10} in this construction is made separate from the 40 arm and is provided with a narrow longitudinal slot d^{11} , having preferably square corners. The knife or cutter E' is constructed preferably as shown in Fig. 10, its shank or attaching portion being slit downwardly, as at e. In securing the knife or cutter to the handle 45 and arm portions the split shank is passed vertically through the said arm and handle portions from the under side and the split portions turned over, as clearly seen in Figs. 50 6 and 7, by which construction and arrangement the knife or cutter will be rigidly attached to the handle and capable of being turned thereby and will be free to turn in the aperture d^9 in the arm. I do not wish to 55 limit myself to the exact manner of securing the knife or cutter to the arm and handle portions, as it is obvious that the construction might be varied without departing from the spirit of my invention, the same consisting 60 of a revoluble cutter in combination with a longitudinally-adjustable pivoted cutter-arm adapted to operate on a square box or can.

The advantage of pivoting the knife or cutter directly to the tagger-top over providing 65 the knife or cutter on the removable cover is that with my construction and arrangement it is not absolutely necessary to employ a re-

movable cover, which fact reduces the expense of manufacture, and in my construction, where a removable cover is employed, 70 should the same become detached from the can before it was opened the cutting operation would not be interfered with, which would not be the case if the cutter were provided on the removable cover. The tagger-top B may be provided with a pocket b, as 75 shown in Fig. 2, for the reception of the knife or cutter during transportation. This pocket would be stamped in the top, but not through the same, and would be deep enough to receive the knife or cutter and allow the same to be practically flush with the upper surface 80 of the top, so as not to interfere with packing one can on top of another, and also avoid any liability of the cutter being accidentally 85 forced through the tagger-top. It is obvious that by locating the pocket or recess on the upper horizontal surface of the tagger-top when it is desired to cut out the latter it can be accomplished by giving the knife a rotary movement without necessarily lifting the cutter out of the pocket. I regard this 90 as a very important feature of my invention, as it enables me to prevent the tagger-top being accidentally punctured by the knife during 95 transportation in a most perfect and simple manner. The formation of a pocket for the reception of a handle would not be necessary where a removable cover, as C, is employed. The tagger-top may also be provided 100 with a slight depression b', which extends all around the can and is of less depth than the pocket b or the cutter, and which would be useful in guiding the knife in its cutting-out operation. 105

My invention differs materially from an auxiliary cutter, which is not pivoted on the tagger-top, but is adapted to be applied to a can having a tagger-top and rotated to cut out the same, as in such a construction great inconvenience and annoyance are experienced by the purchaser in always having the cutter handy and also by the manufacturer in attaching or shipping such auxiliary cutters. 110

In Figs. 11, 12, and 13 I have shown another modified form of my invention. A detail view of the cutter employed in such construction is shown in Fig. 14. In this construction the arm carrying the cutter is made longitudinally adjustable for a purpose now 115 to be described. The arm is constructed of two members f f'. The member f is stamped or punched downwardly to form a cutting-point f², and beyond the cutting-point it is extended to form an operating-handle f³. 120 The inner end of this member f is turned over to form guides f⁴. The member f', which is pivoted to the center of the tagger-top, is formed with lateral extensions f⁵, which engage the guides f⁴ on the member f and prevent the separation of the members, and also allow the outward adjustment of the said members. The downwardly-extending cutting-point f² prevents the separation of the 125 130

members in that direction. The member f' is provided with an aperture f^6 , which is engaged by a pivot-pin f^8 on the tagger-top. The tagger-top is provided with a depression or groove f^9 , and the cutting-point f^2 rests in said groove during transportation. When it is desired to cut out the tagger-top, the cutting-arm is slightly raised, so as to disengage the cutting-point from the groove in the tagger-top, and the member f is drawn out until the cutting-point f^2 is at the outer edge of the tagger-top, and the handle portion will project beyond the outer edge of the can, so that it can be readily grasped between the thumb and forefinger and the cutter revolved to cut out the tagger-top, as clearly seen in Fig. 12. It will be observed that the cutter-arm in this construction will rest flat upon the top of the can and no outer cover is necessary and that a powerful leverage can be secured for cutting out the tagger-top.

In Fig. 15 I have shown the pivot-point secured to the tagger-top without penetrating the same or by the use of solder. This is accomplished by forming the tagger-top with a raised portion G , inclosing a depression g . The pivot-pin g' , having a head g^2 , is dropped into the depression, and a suitable tool is used to turn over the raised portion G onto the head of the pivot-pin, and thus hold the same securely in place.

In Fig. 16 I have shown another slightly modified form of the construction shown in Fig. 11, in which a single cutter-arm H is employed instead of a two-part arm, and this arm is provided with a longitudinal slot h and on its under side with a cutting-point h^2 , similar to the construction shown in Fig. 11. The use of this construction will be precisely the same as the construction shown in Fig. 11, and the can will be provided with a groove or recess to receive the cutting-point. The groove or recess may be in the form of a pocket, as shown in Fig. 2, or it may be in the form of a circle, as shown in Figs. 11 and 12, and I wish my invention to cover the circle whether it is arranged concentrically or eccentrically.

The invention will be found very useful in shipping tobacco, condensed milk, paint, and other articles which it is desired to keep hermetically sealed during transportation and before being opened, and to have a shipping box or can provided with means applied on the tagger-top for cutting out the same.

Having described my invention, what I claim as new, and desire to secure by Letters Patent, is—

1. A box or can comprising in its construction a suitable body portion provided with a permanent thin top and a knife or cutter pivoted on said top, substantially as described.

2. A box or can comprising in its construction a suitable body portion provided on its outer surface near its upper edge with an outwardly-extending projection or projections and with a permanent thin top, a knife or cutter pivoted at the center of the tagger-top,

said knife or cutter being provided with suitable means for operating the same, and a removable cover which rests with its lower edge on the projection or projections on the body of the can, substantially as described.

3. A box or can comprising in its construction a suitable body portion provided with a permanent thin top and a knife or cutter pivoted at the center of the tagger-top, said knife or cutter being provided with suitable means for operating the same, the arm of the cutter being pivoted to the tagger-top by means of a pin which is secured to the upper surface of the tagger-top without puncturing the same, substantially as described.

4. A box or can comprising in its construction a suitable body portion provided with a permanent thin top and a knife or cutter pivoted at the center of the tagger-top, said knife or cutter being provided with suitable means for operating the same, the arm of the cutter being formed with laterally-projecting portions which are adapted to be turned up to form a handle, substantially as described.

5. A box or can comprising in its construction a suitable body portion provided with a permanent thin top and a knife or cutter pivoted at the center of the tagger-top, said knife or cutter being provided with suitable means for operating the same, the arm of the cutter being provided with a longitudinal slot which engages the pivot-pin, whereby the knife can be adjusted longitudinally, substantially as described.

6. A square box or can comprising in its construction a suitable body portion provided with a permanent thin top and a knife or cutter provided with an arm having a longitudinal slot which arm is pivoted at the center of the tagger-top by a pin which passes through the longitudinal slot, said knife being also capable of rotary movement independently of the cutter-arm, substantially as described.

7. A box or can comprising in its construction a suitable body portion provided with a permanent thin top and a knife or cutter pivoted at the center of the tagger-top, said knife or cutter being provided with suitable means for operating the same, and said tagger-top being provided with a pocket or recess in which the knife or cutter is adapted to rest during transportation, substantially as described.

8. A box or can comprising in its construction a suitable body portion having a permanent thin end in combination with an arm or cutter, said thin end being provided with means for pivoting the knife or cutter thereto and also provided with a recess or pocket for receiving the point of the knife, the construction and arrangement being such that the cutter can be shipped with the can without liability of puncturing the same and when desired, revolved to cut open the can, substantially as described.

9. A box or can comprising in its construction a suitable body portion provided with a

permanent thin top and a longitudinally-adjustable cutter-arm pivoted to the can and provided on its underside with a downwardly-extending cutter, the cutter-arm when drawn out projecting beyond the outer edge of the can to form a handle, substantially as described.

10. A box or can comprising in its construction a suitable body portion provided with a permanent thin top having a groove or pocket and a longitudinally-adjustable cutter-arm pivoted on the can and provided on its underside with a downwardly-extending cutter, which, during transportation, rests in the groove or pocket, and the cutter-arm, when drawn out, projecting, beyond the outer edge of the can to form a handle, substantially as described.

11. A box or can having a permanent thin top in combination with a rotatable knife or cutter, said thin top being provided with means for pivoting the said knife or cutter

and also provided with a recess or pocket for receiving the point of the knife during transportation, the construction and arrangement being such that the cutter can be shipped with the can and be drawn out beyond the outer edge of the can to form a handle, and revolved to cut open the can, substantially as described.

12. As an improved article of manufacture, a box or can having a closed end, the said end being provided with a pivot and a pocket, substantially as described.

13. A box or can having a closed end, and provided with a pivot, which pivot is secured to the said end without puncturing the same, substantially as described.

In testimony whereof I hereunto affix my signature in presence of two witnesses.

LOUIS C. WITKOWSKI.
